UNITED STATES PATENT OFFICE

WILLY SCHÜBBE, OF GERA, GERMANY

DRILLING MACHINE

Application filed March 5, 1927, Serial No. 173,095, and in Germany March 3, 1926.

This invention relates to a high-efficiency drilling machine, the chief feature of which resides therein that the drilling spindle is arranged centrally between two columns connected at their lower ends by a foot plate and at their upper ends by a box-like head bridge. Other features consist, firstly, therein that the drilling spindle is driven by a belt tightening gear enclosed in said head bridge and 10 arranged between the shaft of the driving motor located vertically upon the said bridge and the drilling spindle; secondly, in the particular design of the feed gear for the spindle stock or head stock, as well as of the 15 rotatory work table, and finally, of various other mechanisms and members, all as fully described hereinafter.

The invention is illustrated diagrammatically and by way of example on the accompanying drawings, on which Figure 1 is a front-view of the machine, Figure 2 a separate view of the rotatory multiple working table, Figure 3 a plan of this table; Figure 4 shows some details of one of the individual 20 working tables proper, partly in vertical section, and Figure 5 shows also some details also in vertical section, but at right angles to Fig. 4, viz. in the plane A—B of this latter figure; Figure 6 is a plan of the base plate of the machine, Figure 7 a horizontal section through the head bridge in the plane C—D of Fig. 1, this Fig. (7) being drawn to an enlarged scale; Figure 8 is partly a front-view of, and partly a vertical section through, the 25 head bridge, the scale being the same as that of Fig. 7; Figure 9 is a vertical section through the righthand upper part of the machine in the plane E—F of Fig. 1 and drawn to a still more enlarged scale than Figs. 7 and 30 8; Figure 10 is a greatly enlarged front-view of the feeding mechanism (middle portion of the righthand half of Fig. 1, but with another position of the arms 55), and Figure 11 is a horizontal section in the plane G—H of Figs. 45 1 and 10.

On Fig. 1 of the drawing 1 denotes two strong columns or standards of circular section which are connected at their feet by the base plate 7 and at their heads by a strong 50 hollow head bridge 4 that supports the ver-

tical electromotor 6. 2 denotes the boring spindle and 12 a socket attached to the lower end of this spindle and receiving the drill. The spindle 2 is located centrally between the columns 1 and cannot be shifted laterally in the direction to any one thereof. The columns are therefore subjected solely to the action of axially acting forces, but never to a bending stress. 3 denotes the spindle stock or head stock which is guided vertically along the columns 1; that is to say, the columns serve as guides for sleeves 13 and 14 firmly connected, or made integral, with the spindle stock. The weight of the spindle stock is counter-balanced by poises 9 guided within the hollow columns 1 and connected with the spindle stock by chains 10 guided over suitable arranged guide rolls. One of the columns 1 serves also as guide member and holder for three individual working tables 16 carried by brackets 8 projecting forth radially from a sleeve 15 encompassing the respective column 1. Any of the three tables can, therefore, be moved to below the drilling socket 12.

The base plate 7 supports near the other column a switch box 17 enclosing the electrical switches required. 18 denotes an oblique channel for the waste oil, 19 a collecting vessel for the same, and 65 an oil-pump. The driving mechanism for the drilling spindle is designed as follows: The vertical shaft of the electromotor 6 is provided with a pulley 5 (Figs. 7 and 8) driving a larger pulley 22 by means of a belt 21 with the aid of a tension pulley 20. The pulley 22 is affixed to the drilling spindle 2. All these pulleys constitute a belt tightening gearing and are enclosed in the head bridge 4. This latter encloses also the feed-mechanism for the drill. The spindle 2 extends upwards beyond the head bridge proper and is provided near its upper end with a pinion 23 engaging a cog-wheel 24 connected with a pinion 26 engaging a cog-wheel 27. This latter is connected by a short vertical shaft with a cog-wheel 28 (Fig. 9) that meshes with a cog-wheel 29, the shaft of which is provided with a set of change-wheels 30^a 30^b 30^c 30^d, which are of different diameters, as usual, and mesh

with counterwheels 30^e 30^f 30^g 30^h, as shown in Fig. 9. These latter wheels are located on the so-called draw-key shaft 31 (Figs. 7-11) by which the feed-gear 32 (Figs. 8 and 9) is actuated. This gear or mechanism comprises a worm 33 (Fig. 11), a worm-wheel 34 meshing therewith and attached to a spindle 35, and a rack 36 (Fig. 10) by which the drilling spindle 2 is operated.

Although I prefer to locate the change-wheel mechanism within the head bridge, as in Figs. 8 and 9, still, I wish it to be understood that it may be arranged also in the spindle stock.

Throwing the feed mechanism into, and out of, gear is effected by the lever 37, Figs. 1, 10 and 11. When this lever is depressed, oblique teeth 38 shift a member 39 of a clutch 20 rearwardly whereby roof-shaped teeth 40 of this member are made to engage corresponding teeth 41 of the counter-member 25 of the clutch and the rotatory motion of the worm-wheel 34 is transmitted to the spindle 36, the drilling spindle 2 being now moved downwards.

Stopping the forward feed takes place automatically and is effected by the following means: The spindle sleeve 42 is connected 30 with a vertical rod 44 (Fig. 10) which is moved up and down with it by an arm 43, and carries an abutment member 45 by which the depth of the bore is determined. This member is clamped fast to the rod 44 and 35 can be adjusted along it. A projection 46 of the abutment member 45 contacts on the downward movement of the spindle 2 with a release lever 47 and turns it until a pivot 48 to which the lever 47 is secured has been 40 turned so much that a lateral recess 49 (Fig. 11) provided in the projecting other end of said pivot permits the lever 37 to swing back into its former position. This lever had been 45 retained up to then with its opposite end 50 by the edge 51 of the said pivot. The helical spring 52, Fig. 11, which had been compressed when the two members constituting the clutch 39 were coupled with each other, disconnects these members and the oblique 50 teeth 40 and 41 turn the lever 37 into its initial position.

The interruption of the feed may be effected, however, also at will and at any point of time, for instance while the drilling is 55 just going on. There is provided for this purpose a projection 53, Fig. 11, at the lever 47 by which this latter can be turned manually at any desired point of time whereby the actions just described and taking place normally automatically and resulting in the 60 lever 37 re-assuming its initial position can be effected at will at any desired point of time. When the lever 47 is not depressed, it is supported by a helical spring 54, Fig. 10, 65 by which it is held in such a position that the

edge 50 of the lever 37 can co-operate with the edge 51 of the recess 49 of the pivot 48 in the manner described.

From what has been explained appears that only one short manual operation is necessary to throw the feed mechanism into gear, as the closing of the clutch 39 and the checking of the release can be effected simultaneously by one grip. When the release has been effected (automatically or manually), the drilling spindle is lifted by turning the hand cross 55, without no such other manipulation as are required with all other constructions I have become acquainted with. The machine can, thus, be attended to very quickly 75 and the operations can be carried through in quick succession. The machine can, therefore, justly be termed a high-efficiency one.

Concerning, finally, the working tables, their construction is as follows:

It has already been explained that the three working tables (16, Figs. 1-3) are supported by radial brackets 8 extending forth horizontally from a sleeve 15 encompassing one of the columns 1. Vertically below the drilling spindle 2, or the socket 12 respectively, is a standard 57 (Figs. 2, 4 and 5) which serves as support for that working table 16 that is located just below the drill. It is a matter of course, that the work piece to be drilled must be able to withstand the pressure, and it is also necessary to couple the respective table with the standard 57. For this purpose a vertically movable locking bolt 56 (Figs. 2, 4 and 5) is provided which forms a truncated cone at its upper end and is subjected to the pressure of a helical spring 58 by which the locking bolt head is retained in a suitably shaped recess provided in each of the three brackets 8. The locking bolt is connected with a treadle 59 by means of rodding 60 so that it can be withdrawn from the respective bracket by means of said treadle which the workman must depress with one of his feet. When the bolt 56 has been withdrawn, the three tables can be turned around the column 1 by any one of the grips 61. The locking of the next used table (irrespective of the direction of rotation of the three tables) takes place, however, automatically, in that the locking bolt after having been relieved from the pressure of the foot (upon the treadle 57) is again depressed by one or the other (according to the direction of rotation) of two oblique faces 62, Fig. 5, at the upper end of which the conical bolt-top jumps into the recess provided for it in the bottom face of the table.

The top face of each working table is provided with grooves into which flows the surplus of the oil or of the cooling fluid employed while the drilling operation proceeds. That surplus flows then down from said grooves through suitably provided holes into a small chamber 63, Figs. 4 and 5, from which

it is conducted further and away to and through a pipe 64 down upon the base plate 7 in which are provided broad grooves 18, Fig. 6, from which the oil etc. flows to an into a main collecting space 19 near which is provided a pump 65 that presses the oil into a pipe conducting it back to the drill.

I claim:

A drilling machine comprising in combination, a base plate, two spaced vertical columns supported on said base plate, a hollow bridging head supported by the column at the upper ends thereof, a drilling spindle arranged medially between said columns and parallel thereto and vertically slidable through the bridging head, a driving motor having its shaft normal to the bridging head and extending thereinto and laterally of said spindle, a transmission mechanism arranged within the hollow bridging head and connecting the motor shaft with said spindle and including an endless flexible driving member and a tension element, and means arranged partly within the bridging head and operable by the rotation of said spindle whereby said spindle may be moved in either direction, said latter means including change speed gearing located within the hollow bridging head, another spindle within the head and depending therefrom and associated with the said latter gearing, and an operable connection between the second spindle and the first mentioned spindle.

In testimony whereof I affix my signature.

35 WILLY SCHÜBBE.
